UNITED STATES PATENT OFFICE.

EUGENE C. STACY, OF TIFFIN, OHIO.

DRINKING-FOUNTAIN.

1,211,980.

Specification of Letters Patent.

Patented Jan. 9, 1917.

Application filed November 19, 1912. Serial No. 732,225.

To all whom it may concern:

Be it known that I, EUGENE C. STACY, a citizen of the United States, residing at Tiffin, in the county of Seneca and State of Ohio, have invented certain new and useful Improvements in Drinking-Fountains, of which the following is a specification.

My invention relates to an improvement in drinking fountains for poultry, and the object is to provide means for supporting a vessel or can at a sufficient elevation in a pan for causing the pan to be filled with water at a predetermined elevation at all times.

15 The invention consists of certain novel features of construction and combinations of parts which will be hereinafter described and pointed out in the claims.

In the accompanying drawings, Figure 1 is a vertical sectional view through the can and receptacle; Fig. 2 is a view showing the pan partly in section and the can in the position taken as the can is inserted into the pan for fastening the can to the pan; Fig. 3 is a perspective view of the pan; Figs. 4 and 5 are plan views of slight modified forms; Figs. 6 and 7 are vertical sectional views of the forms shown in Figs. 4 and 5 respectively.

30 A, represents the pan disclosed in Figs. 1 to 3, and which is provided with three compartments 1, 1. The pan is formed in the shape of a three-leaf clover, and the wall and bottom of the pan extend inwardly or 35 converge toward the center at three different points as at 2, 2, for forming the compartments 1, 1. The converging portions 2 of the wall are provided with inwardly projecting ridges 3, 3. Two of the converging 40 portions have the upper edges thereof flaring outwardly, while the third converging portion 2 is provided with a groove 4 above the ridge 3. Grooves 5 are formed beneath the other ridges 3.

45 A jar or can B is adapted to be supported by the pan A, and is provided with a flange 6 and collar 7. The flange 6 is placed in the groove 4 of the wall, as indicated in Fig. 2, then the can is forced downward 50 causing the flange 6 to pass the flaring edges 8 and beneath the ridges 3 and enter the grooves 5 beneath the ridges. The collar 7 of the can resting on the upper edge of the wall for holding the can on the pan, and the flange 6 locking the can to the pan. In this 55 manner the can is securely locked or fas-

tened to the pan by the flange 6 entering the grooves 4 and 5. The usual Mason fruit jar can be used if desired as it is provided with a flange and collar.

The form shown in Fig. 4 is very similar to the form disclosed in Figs. 1 to 3, with the exception that the wall converges at the center forming two converging portions 9 instead of three. Two compartments, 1 1 are formed at each end of the pan A from which the animals can drink.

In Fig. 5, the pan A has one end thereof reduced in size forming a constriction. Upon this constricted portion 10 of the wall a groove 11 is formed, similar to the groove 4, for the reception of the flange 6 of the can or jar, and on the opposite side of the constriction a ridge 13 is formed. Above this ridge the edge of the wall flares outwardly as at 12, and beneath the ridge 13 a groove is formed, as is shown at 5 in Fig. 2, for the reception of the flange 6 after the flange is sprung beneath the ridge 13 for the reception of the flange 6 after the flange 80 is sprung beneath the ridge 11.

From the foregoing it will be seen that a very simple means of attachment is provided, by simply having the walls of the pans provided on the inner side thereof with grooves into which the flange on the jar or can is sprung for fastening the jar or can to the pan, and holding the can at an elevation whereby the water in the can will be discharged into the pan as the contents of the pan are consumed, and keep the water in the pan at all times at a predetermined level.

Having fully described my invention, what I desire to secure by Letters Patent, 95 is:

1. In a watering device, the combination with an inverted water reservoir having an opening in its lower end and a projection from the surface around such opening, of a receptacle having sides with reentrant portions approaching closely to the projection around the opening in such reservoir, and projections from such reentrant portions adapted to engage with the first mentioned projection.

2. In a watering device the combination with an inverted jar having a circular mouth and a projection from the surface around such mouth, of a detachable cover for such jar with sides adapted to form a water trough, such sides having reentrant por-

- tions lying in a circle of diameter slightly greater than the diameter of the mouth of such jar, and projections from such reëntrant portions adapted to engage with the projection around the mouth of such jar.
3. In a watering device the combination with an inverted jar having a projection from the surface around its mouth, of a detachable cover for such jar with sides adapted to form a water trough, such sides hav-

ing yielding reëntrant portions with projection therefrom adapted to be sprung into engagement with the projection first mentioned.

In testimony whereof I affix my signature, 15
in the presence of two witnesses.

EUGENE C. STACY.
